UNITED STATES PATENT OFFICE

93,100

DESIGN FOR A VACUUM CLEANER CASING

Lurelle Van Arsdale Guild, Noroton, Conn., assignor to The Singer Manufacturing Company, Elizabeth, N. J., a corporation of New Jersey

Application May 31, 1934, Serial No. 51,971

Term of patent 14 years

To all whom it may concern:

Be it known that I, LURELLE VAN ARSDALE GUILD, a citizen of the United States, residing at Milestone House, Noroton, Connecticut, have invented a new, original, and ornamental Design for a Vacuum Cleaner Casing, of which the following is a specification, reference being had to the accompanying drawing, forming a part thereof.

Figs. 1 and 2 are, respectively, front and rear

perspective views of a vacuum cleaner casing showing my new design.

I claim:

The ornamental design for a vacuum cleaner casing, as shown.

In testimony whereof I have signed my name to this specification.

LURELLE VAN ARSDALE GUILD.
